UNITED STATES PATENT OFFICE.

EDWARD A. HALBLEIB, OF ROCHESTER, NEW YORK, ASSIGNOR TO NORTH EAST ELECTRIC COMPANY, OF ROCHESTER, NEW YORK, A CORPORATION OF NEW YORK.

MACHINE FOR FORMING ARMATURE-COILS.

1,330,317.

Specification of Letters Patent. Patented Feb. 10, 1920.

Application filed July 10, 1915. Serial No. 39,164.

To all whom it may concern:

Be it known that I, EDWARD A. HALBLEIB, a citizen of the United States, and resident of Rochester, in the county of Monroe and 5 State of New York, have invented certain new and useful Improvements in Machines for Forming Armature-Coils, of which the following is a specification.

This invention relates to a machine for 10 forming the coils by which a drum-armature of an electric motor or generator is wound, these coils being wound, tapered, and formed so that they may be applied to the armature by merely introducing them in the 15 slots of the core.

In the winding of the drum-armature a considerable amount of space is occupied, at each end of the armature, by the parts of the coils which cross each other, and accordingly it is desirable, for the sake of compactness, that these parts be fitted as closely as possible together. For this reason the coils, which are of a rectangular form in cross-section, are usually formed with a 25 partial twist in each end-portion, this twist giving them such a form that the several adjacent coils will nest closely together at the ends. One object of the present invention is to produce a machine which will 30 form the twisted end-portion of the coil with great accuracy, so that they will nest as closely together as possible.

In some drum-armatures the slots are not arranged parallel with each other, but are 35 arranged at a slight angle to the axis of the armature. In order to suitably form a coil for entrance into slots so arranged it is necessary that the longer arms or side-members of the coil be arranged at an angle 40 to each other, and another object of the invention is to produce a machine which will secure this angular relation in a simple and accurate manner.

Other objects of the invention, and the 45 features of construction and arrangement by which these various objects are attained, will be set forth hereinafter, in connection with the description of the illustrated embodiment of the invention:

50 In the accompanying drawings:

Figure 1 is a plan-view of a machine embodying the present invention;

Fig. 2 is a left-hand side-elevation of the machine;

Fig. 3 is a front-elevation of the machine, 55 showing the parts in the position occupied at the commencement of the coil-forming operation;

Fig. 4 is a partial vertical median section of the machine, in the position shown 60 in Fig. 3;

Fig. 5 is a left-hand side-elevation of the machine, with certain parts shown in section; and

Fig. 6 is a perspective view of a coil 65 which has been formed by the machine.

The invention is illustrated as embodied in a machine comprising a stationary clamp 10 fixed on the base-plate 11 of the machine. The stationary clamp comprises a fixed jaw 12, and a movable jaw 13 which slides between guides 14. The clamp is operated by a hand-lever 15, having a cam-surface 16 which works against the outer end of the clamp-jaw. A spring 17, coöperating with 70 a pin 18 which projects downwardly from the jaw, acts to open the clamp when the hand-lever is swung to the position of Figs. 1 and 2.

The stationary clamp constitutes means 80 for holding one of the side-members, A, of the coil, and the other side-member B is engaged and moved by a movable clamp. For this purpose a yoke 19 is formed integral with two arms 20, which are pivoted on 85 pins 21 turning in bearing-blocks 22 on the base-plate 11. The fixed jaw 23 of the clamp is integral with the yoke 19, while a movable jaw 24 slides between guides 25 on the yoke, and is operated by a hand-lever 26 90 provided with a cam-surface 27, the lever being pivoted on the yoke. The jaw 24 is retracted by a spring 32 arranged in the same manner as in the case of the stationary clamp. 95

In order that the jaw 24 may grip the coils closely it is arranged to have, in addition to its sliding movement, a movement toward and from the yoke 19. For this purpose it is arranged loosely in the guides 25, 100 and provided with a beveled surface 28. A bar 29, fixed to the arms 20, carries beveled bearing-blocks adjustable by means of screws 31, these blocks coöperating with the beveled surface 28. Coiled springs 33, 105 mounted in sockets in the yoke, tend to press the jaw 24 away from the yoke, as shown in Fig. 2, but when the jaw is ad-

vanced upon the yoke by means of the hand-lever 26 the action of the beveled surface against the bearing-blocks causes the jaw to be moved toward the yoke.

- 5 The yoke is swung about the pivots 21 by means of a handle 34, and when the coil is first introduced in the clamps this handle is held in vertical position, with the movable clamp directly above the stationary clamp, 10 so that the two side-members of the coil, which are then parallel and comparatively close to each other, may be gripped by the clamps. The handle 34 is then swung outwardly and downwardly, thus pulling the 15 side-member B away from the member A, and at the same time rotating it through an angle of 90°. This swinging movement of the yoke is arrested and limited by adjustable stop-screws 36 on the base-plate 11. 20 Incidentally to the relative movement, just described, of the side-members of the coil, the end-members of the coil are drawn out and twisted, and it has been found that the required form may be imparted to these 25 end-members more readily by giving them a preliminary downward bend, as shown in Fig. 3. Accordingly, the clamp-jaw 24 is provided with fingers 35, which extend laterally so as to engage and bend the end-members as shown in Fig. 3.

It has been found that the twist in the end-members which results naturally from the relative movements of the side-members does not give the form which is best adapted to permit the end-members to lie close together when the coils are placed upon an armature. Accordingly, means are provided for controlling the twisting action, these means being in the form of abutments 35 adapted to engage the end-members on opposite sides. As shown particularly in Fig. 1, these abutments comprise rounded pins 37 and 38, between which each end-member of the coil is seated when the coil is placed 40 on the clamps. Each pair of pins is mounted in an arm 39, fixed to a shaft 40 which moves loosely in a perforation in the clamp-block 10, the shafts being free both to turn and to slide. A spring 41 coiled about each 45 shaft 40 and fixed at its ends, respectively, to the clamp 10 and the arm 39, acts both to force the shaft outwardly and to rock it to the position of Fig. 1. The abutments are mounted movably, as just described, in 50 order that they may follow the movements of the end-members of the coil when these members are being stretched and straightened. For the same purpose each arm 39 is provided, below its shaft 40, with a beveled 55 lower extremity or finger 42, as shown in Fig. 1, to coöperate with a beveled surface on a cam 43. The cam is integral with a block 44, which is arranged to swing on a pivot 45. The movements of the block and 60 cam are controlled by a stop-pin 46 and a

spring 47. When the movable clamp is swung forwardly and downwardly the resulting movement of the end-members of the coil causes the abutments and the arms 39 to be swung forwardly with the coil. 70 At the same time the cams 43, acting on the beveled extremities 42, force the arms 39 and the shafts 40 inwardly, to compensate for the straightening of the end-members of the coil and maintain the abutments 75 in engagement with the coil. Just before the completion of the movement of the movable clamp, however, the arms 39 reach a position in which the extremities 42 move past and disengage the cams 43, whereupon 80 the springs 41 force the shafts 40 outwardly, thus disengaging the abutments from the coil, and as soon as the disengagement occurs the springs rock the arms back to their original position. This return movement is 85 arrested by the engagement of the extremities 42 with stop-pins 48 projecting upwardly from the base 11.

The engagement of the end-members of the coil by the abutments 37 and 38 causes the twist of the end-members to be most pronounced at the middle of these end-members, and thus produces a form which has been found most desirable for compactness and arrangement of the windings. 95 The abutments have the further advantage that they serve as supports or guides for the end-members of the coil while it is being placed in the clamps.

After the completion of the operative 100 movement the movable clamp is opened to release the side-member held thereby, and the final forming operation is then performed upon the coil, this operation being that by which the side-members A and B are 105 moved out of their parallel relation and by which the side-member B is moved longitudinally for a short distance with respect to the member A. For this purpose the machine is provided with a rocking member 50 mounted on a pivot-stud 53 on the front of the clamp-block 10. One extremity 51 of the member 50 has a beveled inner surface adapted to engage the outer surface of the end-member C of the coil, while the beveled 110 outer surface of the other extremity 52 is adapted to engage the inner surface of the end-member D of the coil. The member 50 is actuated by a hand-lever 54, (omitted from Fig. 5) and it acts to press the end-member C upwardly and to the left (as seen in Fig. 3), and the end-member D downwardly and to the left. The extent of this movement is determined by an adjustable stop-screw 56 which coöperates with the 115 hand-lever 54, and the lever is returned to normal position by a spring 55.

The operation of the machine as a whole is as follows: With the parts in the position of Fig. 1, the operator places a coil, with 120

its members lying in a vertical plane, into position between the abutments 37 and 38, with its lower side-member lying between the jaws of the stationary clamp. He then 5 swings the hand-lever 15 to cause the stationary-clamp to grip the coils. The operator then swings the hand-lever 34 upwardly and rearwardly to a vertical position, thus bringing the movable clamp into engagement 10 with the upper side-member of the coil, and then closes the movable clamp upon the coil by means of the hand-lever 26. The operator then swings the hand-lever forwardly and downwardly, and during the first part 15 of this movement the end-engaging abutments coöperate with the coil, while they become disengaged therefrom and return to the normal position before the completion of the movement. The operator then opens the 20 movable clamp so as to release the side-member of the coil which is held thereby, and then depresses the hand-lever 54. This completes the operation upon the coil, which is then released from the stationary clamp 25 and removed from the machine. The form imparted to the coil is shown in Fig. 6.

My invention is not limited to the embodiment therof hereinbefore described and illustrated in the accompanying drawings, but 30 it may be embodied in various other forms within the nature of the invention as it is defined in the following claims.

I claim:—

1. A coil-forming machine having, in combination, means for pulling apart and relatively rotating the side-members of a coil; end-forming means for simultaneously engaging the end-members of the coil and controlling the form imparted to them; and 35 means for moving the end-forming means 40

inwardly as the end-members of the coil are straightened.

2. A coil-forming machine having, in combination, means for pulling apart and relatively rotating the side-members of a coil; 45 abutments for engaging the end-members of the coil on opposite sides, to control the twisting thereof; supports, for said abutments, arranged to swing about an axis close to the axis of movement of the first mentioned means; and cams for moving said supports inwardly during such swinging movement to cause them to follow and remain in engagement with the end-members. 50

3. A coil-forming machine having, in combination: means for gripping and holding one of the parallel side-members of a coil, means for acting upon the other portions of the coil so held, to separate the side-members and bring the longitudinal axes of the 60 side-members out of their original common plane and means to bring said axes into an angular relation. 55

4. A coil-forming machine having, in combination, means for gripping and holding 65 one side-member only of a coil, while the other side member is left free; and means for engaging the end-members of the coil so held and pressing them in opposite directions to move the other side-member both 70 longitudinally and angularly with respect to the first-mentioned side-member.

5. A coil-forming machine having, in combination, means for drawing a round-ended coil into approximately rectangular form 75 with twisted end-members; and means for bending the coil thereafter into the form of a twisted rhomboid.

EDWARD A. HALBLEIB.
